United States Patent Office.

THOMAS WRIGHT, OF NEW YORK, N. Y., ASSIGNOR TO JOHN A. HOLMES, OF SAME PLACE.

Letters Patent No. 99,512, dated February 1, 1870.

IMPROVED BROOM FOR STABLES, &c.

The Schedule referred to in these Letters Patent and making part of the same

To all whom it may concern:

Be it known that I, THOMAS WRIGHT, of the city and State of New York, have invented and made an Improvement in Brooms for Stables, &c.; and the following is hereby declared to be a full, clear, and exact description of the same.

Brooms have heretofore been made of cane and similar material, bound upon a handle by a wire, and then bent double and bound around a second time with wire, but the same does not make a firm head for the broom, because the material is of a very stiff or rigid quality, and the wire does not hold the mass sufficiently tight to the handle.

My invention, as distinguished from the mode of manufacture heretofore adopted, consists in a metal ring, containing the cane, and into which the tapering end of the handle is driven, so as to compress the canes firmly within said ring, and then the ring is secured to the handle by nails or screws, and the cane turned over the ring, or doubled and spread and clamped, to form the broom.

In this mode of construction, the fibrous materials are confined by the band, in a manner similar to that employed in making paint-brushes, but the canes or fibres are folded over or doubled, and I here remark that the doubling of the fibres, I am aware, has been employed with a wire, as in the manufacture of hair-brushes, tooth-brushes, &c.

In the drawing—

Figure 1 shows a broom complete, and

Figure 2 is an elevation of the bunch of fibre within the ring.

The ring *a*, containing the bunch *b* of canes or other fibres, also receives the tapering end of the handle *c*, the latter being driven in to wedge the fibres tightly

within the ring *a*, and then nails or screws *d* are inserted, to hold the ring *a* firmly in place.

The canes *b* or elastic fibre being softened or pliable, are bent over, as indicated by the dotted lines, fig. 2, and spread into a broom-form, (fig. 1,) between suitable clamps.

The metallic band *f* is applied to hold the broom in shape.

Said band is made of two pieces, united by rivets at *e*, so that the two parts may be turned upon said rivets, to any desired angle to each other, and thereby be made to conform to the angles of inclination of the edges of the broom.

Nails passing through the bands *f* and broom, as at *i*, and either clinched or riveted, serve to hold the parts firmly together.

The ornamental cap *h*, made of a cylinder surrounding the handle, and a flange, covering the bend of the canes, is employed to form a finish at the junction of the handle and canes. This cap also aids in holding the canes or fibres at point at which they are doubled, by preventing the exterior portions driving up, and bending outwardly and upwardly at said point where the canes are doubled.

What I claim as my improvement, in the construction of brooms with folded fibres, is—

The ring *a*, nails or screws *d*, and tapering handle *c*, as shown, in combination with the clamp *f*, for confining the folded fibres, as specified, and, in combination with the foregoing, the cap *h*, as and for the purposes described.

Signed by me, this 6th day of January, A. D. 1870.

Witnesses:

THOS. WRIGHT.

CHAS. H. SMITH,
GEO. T. PINCKNEY.
